(57) **CLAIM**

The ornamental design for a cycle suspension assembly, as shown and described.

DESCRIPTION

FIG. 1 is a top, front, and right side perspective view of a cycle suspension assembly showing our new design; FIG. 2 is a top, rear, and right side perspective view thereof; FIG. 3 is a front elevation view thereof; FIG. 4 is a rear elevation view thereof; FIG. 5 is a right side elevation view thereof; FIG. 6 is a left side elevation view thereof; FIG. 7 is a top plan view thereof; and, FIG. 8 is a bottom plan view thereof.

The broken lines in the drawings illustrate portions of the cycle suspension assembly that form no part of the claimed design. The dash-dot broken lines indicate boundaries of the claimed design.
